Primary Examiner — Paula Greene

(57) **CLAIM**

The ornamental design for a knob and handle gripping device, as shown and described.

DESCRIPTION

FIG. 1 is a perspective view of a knob and handle gripping device showing my new design;
 FIG. 2 is a top plan view thereof;
 FIG. 3 is a bottom plan view thereof; and,
 FIG. 4 is a right side elevational view thereof, the left side view being a mirror-image.

1 Claim, 4 Drawing Sheets

FIG 1

FIG 2

FIG 3

FIG 4
